UNITED STATES PATENT OFFICE.

JOHN O'CONNOR, OF NEW YORK, N. Y., ASSIGNOR OF ONE-HALF TO JOHN GOODCHILD, GUARDIAN, OF SAME PLACE.

BOTTLE OR SIMILAR RECEPTACLE.

SPECIFICATION forming part of Letters Patent No. 655,887, dated August 14, 1900.

Application filed October 27, 1899. Serial No. 734,915. (No model.)

To all whom it may concern:

Be it known that I, JOHN O'CONNOR, a citizen of the United States, residing in the borough of Manhattan, in the city, county, and 5 State of New York, have invented certain new and useful Improvements in Bottles or Similar Receptacles, of which the following is a specification.

This invention relates to that class of bottles and similar receptacles for liquids which when once emptied cannot be refilled or at least cannot be refilled except at an expense or cost too great to permit of their being used a second time.

15 In the accompanying drawings several forms of the invention are shown.

Figure 1 is an axial section of the neck of a bottle provided with my invention. Fig. 2 is a side elevation of the tubular neck-plug 20 detached. Fig. 3 is a side elevation, and Fig. 4 a plan or end view, of the caging-plug detached; and Fig. 5 shows the hollow buoyant valve in plan and elevation, detached. Fig. 6 is a view similar to Fig. 1, but showing the 25 valve-seat formed integrally with the bottle. Fig. 7 is a view similar to Fig. 1, but showing the device mounted in a tube which is inserted in a bottle-neck. Fig. 8 is a view illustrating a construction wherein the neck-plug 30 and caging-plug are made integral or in one piece. Fig. 9 shows the bottle of Fig. 1 tilted for pouring out the liquid contents.

Referring first to Figs. 1 to 5, inclusive, X represents a bottle, of which x is the neck. 35 The device which prevents the refilling of the bottle is fitted into the neck thereof, and this device will now be described.

A valve-seat 1, properly ground and provided with a packing-ring 2, of cork, rubber, 40 or other suitable soft material, is fitted into the bottom of the neck and supported on a bead or ledge 3, formed on the bottle, and in or on this seat is a suitably-ground valve 4. This valve will be thin and hollow, so as to 45 be light and buoyant. A ball 5 rests, normally, on the valve and occupies a cage 6 in the neck. This cage is formed by a caging-plug 7, a cavity 7^a in the bottom thereof forming the upper part of the ball-cage. This 50 cavity will be of conical form, so that its

sides all around present an incline to the axis of the bottle-neck. Above the plug 7 and connected therewith is a tubular neck-plug 8. This plug fits down into the bottle-neck, is provided with a packing-ring 9, of cork, 55 rubber, or other yielding material, and has or may have a flange 8^a at its top to rest on the bottle at its mouth and limit the extent to which the plug 8 can be pushed down into the neck. At its lower end the plug 8 has an 60 outwardly-flared nipple 8^b, which engages an undercut transverse groove 7^b in the top or upper end of the plug 7. The purpose of this coupling together of the plugs 7 and 8, as described, is to prevent the plug 7 from 65 descending too far into the neck, and by making the parts 7 and 8 separate or non-integral the ring 9 may be slipped into place without cutting it. However, it is feasible to make the plugs 7 and 8 in one piece or integral, as 70 shown in Fig. 8; but in that case the packing-ring 9, if of cork, will have to be cut or in two sections in order to place it.

Fig. 9 shows the position assumed by the ball and valve in pouring out the liquid from 75 the bottle. To displace the ball, so that the valve may open, the neck must be inclined until the inclined surface of the conical recess in the caging-plug 7 assumes a horizontal position, at least, before the ball will roll away 80 from the valve of itself. The liquid flows past the valve into the caging-chamber, and thence by way of channels 10, variously formed in the exterior surface of the plug 7 and apertures 11, suitably provided in the 85 lower end of the plug 8 to the bore 12 in said plug, and thence out to the mouth of the bottle. y represents the removable cork that closes the mouth of the bottle, and 13 represents a circumferential channel formed partly 90 in the interior of the bottle-neck and partly in the exterior surface of the plug 8. This channel is to receive a suitable cement for cementing the plug in place. The several parts—namely, the valve-seat 1, the buoyant 95 valve 2, the ball 5, and the plugs 7 and 8—will be by preference molded from glass or like material, and the fit of the plug 8 in the bottle-neck will be free or loose enough to permit of putting in a suitable liquid cement, 100

which latter should be of such a nature as to resist all ordinary agencies for displacing it or softening or dissolving it.

In attempting to fill the bottle by inverting it and forcing a liquid upward through the neck the buoyant valve will be floated up to its seat, and to insure this result the ball 5 and recess 7^a will have such proportions that the ball will not permit the valve when the bottle is inverted to entirely disengage itself from the deeply-recessed conical valve-seat.

The valve and ball cannot be reached by a wire or other instrument inserted through the bore 12 in the plug 8, as this bore is axially situated, while the channels or passages 10 are situated next the bottle-neck. Preferably the channels or passages 10 will be formed by a series of circumferential grooves in the plug 7 and channels extending lengthwise of the plug and connecting the circumferential grooves. These latter channels connect below with the ball-cage 6 and above with the bore or passage 12 by way of lateral passages.

25 The valve-seat may be formed integrally with the bottle-neck, as shown in Fig. 6, wherein 1^a is the valve-seat thus integrally constructed.

30 The device to prevent refilling may be mounted in a tube distinct from the bottle, and thus adapted to be placed in the neck of a bottle and cemented in place. This construction is illustrated in Fig. 7, wherein 14 is the tube, preferably of glass, adapted to 35 slip down into the neck of the bottle and be cemented therein. There may be a groove or channel 15 similar to the groove 13 to receive a body of the cement. In the construction shown in Fig. 7 the valve-seat 1^b is formed 40 integrally with the tube 14. The tube 14, it will be noted, occupies the place of the bottle-neck of the construction seen in Fig. 1. The ball 5 might be a marble of the proper size.

45 The channels 11 in the plug 7 may cut through the thin lower edge of the plug produced in forming the conical recess or cavity in the bottom thereof; but this is not important and will not interfere with the rolling of 50 the ball over the inclined surface of the cavity 7^a. The tortuous channels 10, 11, and 12, through which the liquid flows, are formed in the closure above the valve, and this closure thus guards the valve against being tampered with. The ball is in the nature of a 55 loose weight to hold the valve to its seat, its spherical form permitting it to move freely.

Obviously this invention is not limited to any special mode of cementing the parts in the bottle-neck; but it may be stated that 60 the mode I prefer to employ consists in providing the plug 8 with a groove or channel 16, Fig. 2, extending from the flange 8^a down to the groove or recess 13. The plug 8 is entered and pushed down until the cork 9 is just below the recess 13 and liquid cement poured 65 into the channel 16 and allowed to flow down and fill said recess. The plug is then pushed down and the cement allowed to harden in the circumferential space formed at 13. The 70 purpose of the cork 9 is merely or mainly to keep the cement from flowing past the channel to receive it.

Having thus described my invention, I claim—

75 1. In a device to prevent the refilling of a bottle, the combination with a neck-closure, comprising a tubular plug adapted to fit in the bottle-neck, said plug being provided with a cement-groove, and having a reduced and 80 flared inner end, and a solid, exteriorly-grooved plug having a transverse, dovetail recess in its top to receive the flared inner end 85 of the tubular plug, and a conical cavity in its lower face, of a buoyant valve, and a ball thereon, substantially as set forth.

2. In a device to prevent the refilling of a bottle, the combination to form a neck-closure, of a tubular plug 8 having a flange 8^a at its outer end, a circumferential cement-groove 13, a reduced inner end and a packing-ring 9 just below said cement-groove, and a solid, exteriorly-grooved plug 7, said plug 7 having a dovetail, transverse recess 7^b 90 extending across its top and engaged by the 95 flared inner end of the plug 8, substantially as set forth.

3. In a device to prevent the refilling of a bottle, the combination to form a neck-closure, of a tubular, flanged plug, having a cement-groove, and a flared inner end provided 100 with apertures 11 at its end, and a solid plug with channels in its exterior surface to communicate with the apertures 11, said solid plug having in its upper surface a transverse, 105 dovetail recess to receive the flared inner end of the tubular plug, substantially as set forth.

In witness whereof I have hereunto signed my name, this 24th day of October, 1899, in the presence of two subscribing witnesses.

JOHN O'CONNOR.
